UNITED STATES PATENT OFFICE

LUCIEN VILT, OF LILLE, FRANCE

TEXTILE APPARATUS

Application filed March 29, 1930, Serial No. 440,132, and in France May 11, 1929.

The present invention relates to textile apparatus.

One of the objects of the invention is to provide improved means for skimming and polishing textile threads.

Other objects will appear in the course of the detailed description now to be given with reference to the accompanying drawings, in which:—

10 Fig. 1 shows, in plan, one illustrative embodiment of the invention;

Fig. 2 is a similar plan view with certain elements removed;

Fig. 3 is a section taken on line 3—3 of 15 Fig. 1;

Fig. 4 shows part of the assembly detached from Fig. 1.

Referring to Figs. 1 to 4 of the drawings, there is shown a plate 1 (casting or the like) 20 split centrally and provided with a pair of lateral flanges or guides 2, and having an elongated slot 3, formed therein,—a steel plate 6 having a polished edge 8 forming a small angle ϕ with edge 4 of plate 1, edges 25 4 and 8 coming into contact at point 7,—a U-shaped yoke 9 mounted to lie across plates 1 and 6 and provided with a surface 10 adapted to contact with a thread traversing the space between edges 4 and 8,—a limiting wall 11 adapted to coact with surface 30 10 to act on a thread and mounted integrally with a lever 12,—a pin 13 rigidly mounted on lever 12 and positioned to slide in an oblique slot 15 formed in plate 1,—a screw 14 35 mounted on yoke 9 and acting as a pivot for elements 11, 12,—a thread guide 16, 17 mounted on stem 18 and adapted to slide along slot 3,—means for fixing stem 18 in any desired 40 position consisting of a pair of screws 19, 23 engaging with threads 22 of said stem,—and a thread-guide 21 placed under the divergent slot limited by edges 4 and 8.

The operation of the device is practically self-evident from the description: nuts 19 and 23 are first loosened and yoke 9 slid along slot 3 until edges 4 and 8 limit a proper aperture for passage of the thread, the movement of pin 13 in slot 15 changing the distance between surfaces 10 and 11. It suffices to tighten

nuts 19 and 23 to fix the device in any position of adjustment.

What I claim is:—

1. In a textile apparatus, a support provided with a slot having divergent edges, 55 guiding means for directing a thread into said slot, said guiding means being displaceable in the direction of the length of said slot, means for locking said guiding means in any one of a plurality of positions, a 60 pair of spaced walls positioned to cross the direction of said divergent slot, and means operative by the displacement of said thread guiding means to displace one of said walls relatively to the other. 65

2. In a textile apparatus, a support having a guiding slot formed therein, thread guiding means mounted in said guiding slot, means for locking said thread guiding means in position, a plate mounted on said support 70 so that said support and said plate limit a divergent slot therebetween, a yoke supported on said plate, said yoke having one edge thereof positioned to lie across the divergent slot formed by said support and said plate, 75 a limiting wall positioned in spaced relation to said yoke and so as to lie across the divergent slot formed by said support and said plate, and means operative to displace said limiting wall. 80

3. In a textile apparatus, a support having a guiding slot formed therein, thread guiding means slidably mounted in said guiding slot, means for locking said thread guiding means in position, a plate mounted on 85 said support so that said support and said plate limit a divergent slot therebetween, a yoke supported on said plate, said yoke having one edge thereof positioned to lie across the divergent slot formed by said support and said plate, a limiting wall positioned in 90 spaced relation to said yoke and so as to lie across the divergent slot formed by said support and said plate, and means operative by movement of said thread guiding means in 95 said guiding slot to displace said limiting wall relatively to said yoke.

In testimony whereof I affixed my signature.

LUCIEN VILT.
